CLAIM

The ornamental design for a scooter rack, as shown and described.

DESCRIPTION

FIG. 1 is a front and top perspective view of a scooter rack showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another front and top perspective view thereof, shown in an environment with scooters.

The evenly dashed broken lines showing scooters in FIG. 9 illustrate environment and form no part of the claimed design. The remaining evenly dashed broken lines in the drawings illustrate portions of the scooter rack that form no part of the claimed design.
